FIG. 4

UNITED STATES PATENT OFFICE.

HARRY A. LEWIS, OF NORRISTOWN, PENNSYLVANIA.

FEED-ROLLER APPARATUS FOR ROLLING-MILLS.

1,356,535.

Specification of Letters Patent.

Patented Oct. 26, 1920.

Application filed October 23, 1919. Serial No. 332,605.

To all whom it may concern:

Be it known that I, HARRY A. LEWIS, a citizen of the United States, and resident of Norristown, in the county of Montgomery and State of Pennsylvania, have invented a new and useful Improvement in Feed-Roller Apparatus for Rolling-Mills; and I do hereby declare the following to be a full, clear, and exact description thereof.

10 My invention relates to feeding apparatus for rolling mills.

One object of my invention is to provide a simple and efficient form of feeding apparatus for rolling mills in which the metal 15 being rolled is automatically turned and delivered to the receiving side of the rolls or, in the case of a three-high mill, is delivered to the upper pass.

Another object of my invention is to provide apparatus for re-rolling sheets and plates in which the scale which forms upon the metal during the rolling process is effectively removed, this result being accomplished by inverting the metal between successive reductions and thereby bending the metal alternately in opposite directions.

To these ends my invention comprises the novel features hereinafter set forth and claimed.

30 In the drawings Figure 1 is a plan view of a rolling mill showing my invention applied thereto; Fig. 2 is a section on the line 2-2, Fig. 1; Fig. 3 is a cross-section on the line 3-3, Fig. 1; and Fig. 4 shows my invention as applied to a three-high mill.

In the drawing the numeral 2 designates suitable housings of a two-high mill in which the rolls 3 are mounted in the ordinary manner and adapted to be driven in opposite directions, by suitable mechanism, as shown by the arrows on Fig. 2.

In front of the rolls is an ordinary roller-table 4 provided with the feed-rollers 5, said feed-rollers being driven in any suitable way, such as by the bevel-gears 6 which are engaged by the bevel-gears 7 on the outer driven-shaft 8. In this manner the feed-rollers 5 are driven in the direction of the arrows on Fig. 2, so that the metal deposited thereon is fed to the pass between the rolls 3.

In the rear of the housings 2 is located the return feed mechanism, which I will now describe.

55 Mounted on a frame 9 is a curved guide 10 provided at intervals with idle-rollers

11. In front of the curved guide 10 and at a higher elevation in the frame 9 is a like curved guide 12 with idle-rollers 13.

These curved guides 10 and 12 form the supports for the feed-member or cage 14 which has the annular flanges 15 and 16 which engage the grooved anti-friction rollers 11 and 13, respectively, of the curved frames 10 and 12.

65 An inwardly tapering frame 17 is secured within the cage 14 and said frame carries upper and lower sets of idle rollers 18 and 19, respectively. The sets of rollers 18 and 19 form inclined guide-ways 25 and 26, which are adapted to receive the sheet or other metal being worked, and stop-plates 20 are provided to prevent the sheet or other object being rolled from sliding out of the outer end of the cage. The idle 75 rollers in each set may be arranged for adjustment toward and from each other in any desired way, in order to provide for handling sheets and plates of various thicknesses.

70 A suitable guide 21 is provided to direct the sheet between the rollers 18 or 19 according to which set is in the lowermost position.

80 Side guides 30 may also be provided for 85 preventing the material from slipping out of the cage while the cage is being revolved. These guides may be arranged for adjustment in any desired way, to accommodate sheets or plates of different widths.

90 A circular rack 22 is formed on the feeding member or cage 14 and said rack is engaged by the pinion 23 which is mounted on the shaft 24. In this manner rotary movement is imparted to the cage 14.

95 When my invention is employed in connection with a two-high mill, the sheet 28 or other metal object to be rolled is delivered upon the feed-rollers 5, and is carried by said feed-rollers into the pass between the rolls 3. The sheet is delivered by the rolls 3 through the guides 21 to the space between the lowermost set of rollers, which in the case illustrated in Fig. 2 are the rollers 19. The action of the rolls 3 105 will be such as to slightly bend or curve the plate as indicated by dotted lines in Fig. 2 and in this position the plate is delivered between the rollers 19, being supported on the lower set of said rollers. The stop-plate 20 keeps the plate from sliding from the rollers. When the sheet has been de-

65

110

livered in this manner to the cage, power is applied to rotate said cage through the driven pinion 23 engaging the rack 22, whereupon said cage is rotated and the sheet is carried up to the position indicated by dotted lines, Fig. 2, whereupon by its own weight, it slides down the rollers over the guide roll 31 and over the top roll of the mill, whence it drops upon the feed-rolls 5 in position to be again passed through the rolls 3. In this manner, after each pass, the sheet is reversed so that that which was the bottom side in passing through the rolls becomes the top side upon the turning of the cage. This reversing of the sheet each time permits the scale to drop off and the bending of the sheets alternately in opposite directions in the rolls also aids in dislodging the scale. Consequently a better surface is obtained, and so much scale does not adhere to the rolls.

In this manner, the sheet is delivered through the rolls and is automatically reversed and delivered back to the feed side 25 of the roll without manual labor, which greatly facilitates and increases the rolling and reduces the cost of production.

In Fig. 4 I have illustrated my invention in connection with a three-high mill where 30 the sheet, on its being reversed in the cage, is delivered by the pinch feed-rollers 27 back through the upper pass of the mill to be delivered on the feed-table, to be again passed through the lower pass as in the ordinary 35 operation of a three-high mill.

The cage 14 may be given its step-by-step rotation, always in the same direction, or it may, if desired, be oscillated, first in one direction and then in the other. As a further 40 modification, more than two sets of the blank-holding guides 18 and 19 may be provided, the guides or holders in every case being equally spaced around the periphery of the cage 14, and the step-by-step rotation 45 of the cage 14 being so adjusted that each step brings the next empty holder into position to receive a sheet and brings the next full holder into position to discharge its sheet.

50 While I have illustrated my invention in connection with the rolling of a sheet of metal it is apparent that it may be employed for the rolling of other shapes and I do not wish to limit myself in that manner to any 55 particular form of material to be rolled.

What I claim is:

1. In feed mechanism for rolling mills, the combination with the rolls, of means for receiving the material from the rolls, means for inverting the material laterally with respect to the direction of movement of the material through the rolls and for moving the said material to another level, and means for returning the material for re-65 rolling.

2. In feed mechanism for rolling mills, the combination with the rolls, of means for receiving the material from the rolls, means for inverting the material laterally with respect to the direction of movement of the material through the rolls and for lifting the said material to a higher level, and means for returning the material for re-rolling.

3. In feed mechanism for rolling mills, the combination with the rolls, of means for receiving the material from the rolls, means for inverting the material and moving the same to another level, and means for returning the material by its own gravity for re-rolling.

4. In feed mechanism for rolling mills, the combination with the rolls, of means for receiving the material from the rolls, means for inverting the material and lifting the same to a higher level, and means for returning the material by its own gravity for re-rolling.

5. In feed mechanism for rolling mills, the combination with the rolls, of a member revoluble across the direction of movement of the material through the rolls, the said member having oppositely arranged supports to receive the material from the rolls, whereby when said member is rotated the material is inverted and moved to a different level.

6. In feed mechanism for rolling mills, the combination with the rolls, of a member revoluble across the direction of movement of the material through the rolls, the said member having oppositely arranged compartments to receive the material from the rolls, whereby when said member is rotated the material is inverted and raised to a higher level.

7. In feed mechanism for rolling mills, the combination with the rolls, of a rotary member having oppositely arranged inclined supports to receive the material from the rolls, whereby when said member is rotated the material is inverted and elevated to a higher level.

8. In feed mechanism for rolling mills, the combination with the rolls, of a rotary member with oppositely arranged compartments formed of idle rollers arranged on an incline, whereby when said member is rotated the material received between said rollers is inverted and lifted to a higher level.

9. In feed mechanism for rolling mills, the combination with the rolls, of a rotatable work-handling cage having its axis of rotation perpendicular to the plane of the axis of rotation of said rolls, and a work-holder carried by said cage and adapted to receive material from the rolls.

10. In feed mechanism for rolling mills, the combination with the rolls, of an annular cage rotatable on an axis substantially perpendicular to the plane of the axis of rotation of said rolls, anti-friction rollers for 180

rotatably supporting said cage, and a plurality of work-holders equally spaced within said cage and adapted to receive material from the rolls.

5 11. In feed mechanism for rolling mills, the combination with the rolls, of a flaring rotatable work-holding cage disposed with its smaller end adjacent to said rolls, and a plurality of work-holders carried by the 10 said cage at an outward inclination with respect to said rolls and adapted to receive material therefrom.

12. A rolling mill comprising a set of reducing rolls, positively actuated means for 15 feeding material to the rolls, a holder for receiving material from said rolls, and means for rotating said holder on an axis substantially perpendicular to the plane of the axis of rotation of said rolls to invert the 20 material and for returning the material, and delivering it again to said feeding means, whereby the material may be passed through the rolls a plurality of times.

13. A rolling mill comprising a set of 25 reducing rolls, a feed table provided with positively driven rollers for feeding material to said rolls, a rotatable cage disposed adja-

cent to said rolls and rotatable on an axis substantially perpendicular to the plane of the axis of rotation of said rolls, holders carried by said cage for receiving material from said rolls, and means for returning said material from said holder to said feed table, whereby the material may be passed through the rolls a plurality of times. 30

14. Work-holding apparatus comprising a work-holder, means for delivering an article to said holder, and means for revolving said holder on an axis substantially perpendicular to the plane of the axis of rotation of the 40 said rolls and for delivering said article therefrom.

15. Work-holding apparatus comprising a work-holder, means for delivering a flat article to said holder, and means for revolving said holder on an axis substantially perpendicular to the plane of the axis of rotation of the 45 said rolls to invert said article.

In testimony whereof I, the said HARRY A. LEWIS, have hereunto set my hand.

HARRY A. LEWIS.
